UNITED STATES PATENT OFFICE.

HENRY T. HAZARD, OF LOS ANGELES, CALIFORNIA.

MAGAZINE FIRE-ARM.

SPECIFICATION forming part of Letters Patent No. 279,242, dated June 12, 1883.

Application filed June 10, 1882. (No model.)

To all whom it may concern:

Be it known that I, HENRY T. HAZARD, of the city and county of Los Angeles, and State of California, have invented a certain new and useful Improvement in Magazine Fire-Arms; and I do hereby declare that the following, when taken in connection with the accompanying drawings and the letters of reference marked thereon, is a full, clear, and exact description of the same.

This invention relates to an improvement in that class of magazine fire-arms in which the magazine is arranged longitudinally beneath the barrel.

15 The object of my invention is to make a magazine fire-arm that is simple, safe, and reliable, to do away with the cumbersome length and complicated mechanism of magazine-arms, and at the same time render the arm effective 20 and convenient either as a magazine-gun or as a single breech-loader.

25 My invention consists in a vertically-moving solid carrier-block, forming part of the barrel when the arm is closed, a longitudinally-moving locking-bolt, in combination with an operating-lever pivoted in front of the carrier and beneath the magazine, and provided with means for giving the carrier and the bolt an intermittent movement, whereby as the lever 30 is depressed the bolt is first withdrawn and the arm cocked. The carrier is then depressed into line with the magazine, that the empty shell may be ejected therefrom by the impact of the loaded cartridge forced thereon, and at 35 the reverse motion of the lever the carrier is again elevated, and the bolt, returning, locks the carrier in place, as before.

40 My invention further consists in a slide which, by its longitudinal movement, prevents the escape of gas as the cartridge is exploded from the bore of the arm to the magazine and is operated by the locking-bolt.

45 Referring now to the accompanying drawings, Figure 1 is a longitudinal sectional view of the arm closed. Fig. 2 is a longitudinal sectional view of the arm opened; Fig. 3, a perspective view of the carrier-block and shell-extracting band V. Fig. 4 is a sectional view on the line z z of Fig. 1. Fig. 5 is a sectional 50 view on the line y y of Fig. 2. Fig. 6 is a plan view of the locking-bolt M, with its plate L,

on which is formed the lug H and the slide E. Fig. 7 is a perspective view of the carrier on the opposite or right side, showing the concave groove C; Fig. 8, a view showing the breech mechanism of the gun.

A represents the barrel, and B the magazine, extending beneath the barrel and opening into a mortise, X, in the frame in which the carrier-block moves.

60 The carrier-block C is a solid piece of metal, and of sufficient size to fill the mortise or receiver X in the frame wherein it moves. It is formed with a groove, J, which engages the finger K on the arm of the lever, and is thereby operated vertically in the mortise X. The finger K also moves in the slots N in the plate L of the locking-bolt M, which is thereby operated longitudinally, first receding and cocking the arm and unlocking the carrier-block, 70 which will fall in line with the magazine, where it remains until the reverse movement of the lever again elevates it.

75 It will be seen that at the moment the carrier-block C has been elevated into line with the bore of the arm it will then remain stationary, the force of the lever being then lost by reason of the shape of the groove in the carrier, and the force meanwhile is transferred to the plate of the locking-bolt and reciprocates it 80 forward, locks the carrier in place, and removes the extension on the locking-bolt from the hammer, leaving it free to fall. At the rear end of the bore it is properly grooved out, so that the flange of the shell may fit 85 snugly therein, a like groove being formed on the upper part of the carrier-block, which, when locked and in position, forms a continuous groove for the reception of the flange of the shell.

90 The carrier-block is provided with a band, V, that fits in a corresponding groove in the upper rear end of the barrel. This band V will move the empty shell down with the carrier as the carrier moves down into line with the magazine, and the empty shell will remain on the carrier until forced therefrom and out of the arm through the channel F by the impact of the cartridge next ahead of it. This band V is movably affixed to and works in the 95 groove S in the carrier-block, and its upper projection is so shaped as to properly fit the

upper half of the shell while the arm is locked; but when the carrier is depressed into line with the magazine it will be elevated, so as to permit the passage thereunder of the flange of the loaded shell. This is effected by means of a stationary shoulder, U, affixed to the walls of the mortise in which the carrier moves, which projects into the groove S and stops the band as the carrier is moving down and before it gets into line with the magazine, thereby leaving the space for the passage thereunder of the flange of the loaded shell.

The movement of the guard G is continuous; not so the carrier or the locking-bolt, each of which has an intermittent movement as compared with the guard. While the guard is being depressed the locking-bolt is operated on by the finger on the arm of the guard, the finger meanwhile traveling in that part of the slot in the carrier where its force is lost, because the slot of the carrier at this point follows the line of travel of the finger K, the carrier remaining stationary; but when the bolt is clear out and the carrier unlocked the finger will have reached that part in the slot in the carrier which is so formed that by the further movement of the lever it will cause the carrier to move down into line with the magazine, the finger in the meanwhile traveling in that part of the slot in the bolt which is similar in shape to the line of travel of the finger, and the bolt will remain stationary until the carrier has been depressed and again returned to its elevated position and forms part of the chamber, when the bolt will again advance and lock the carrier in position as before.

Heretofore in all breech-loading arms the cartridge is forced into the rear open end of the barrel, and usually in magazine-arms by what is called the "breech-bolt." This bolt incloses the firing-pin, and the complicated mechanism of these arms often causes the pin to advance and explode the cartridge before the same is fully in the bore of the gun. After the gun is fired the shell is withdrawn from the chamber by catches or lugs formed on springs that project into the chamber and engage the flange of the shell. If either is defective or should break, the shell will remain in the chamber, and the arm is then disabled. Often the bullet, protruding from the shell, is left in the chamber when it is attempted to withdraw the cartridge without firing, which will also disable the arm. This cannot occur when the cartridges are fed to and the shell removed from the arm after the manner here shown.

To move the empty shell from the carrier as it is brought in line with the magazine, and at the same time arrest the loaded cartridge forced thereon, a spring, Q, is provided, which is placed in a mortise formed in the rear walls of the space or slot X, its upper free end extending out and into said space, and the lower end being fastened in the mortise in the rear wall. The side of this spring Q will project sufficiently far into the line of the movement of the

cartridges to engage only the flange of the shell. This flange will be forced by this spring as it is elevated into the bore of arm when the carrier rises, and as the empty shell (or loaded, if the arm has not been fired) returns the flange will drop in the rear of the spring and be forced from the carrier and out of the arm by the advance of the loaded cartridge, which will replace it. The loaded cartridge is arrested on the carrier by contact of the flange on its shell with spring Q. A like spring has been employed for a like purpose.

In all magazine-guns now in use of which I am aware a long space is provided in the breech for the movement of the carrier-block, and behind this is usually a long space for the operation of the breech-bolt. The arrangement here shown, however, enables me to construct a single breech-loader with a perfect magazine attachment without in any degree lengthening the frame of the gun or adding thereto any complicated or cumbersome mechanism so liable to get out of order. The magazine mechanism remains stationary while being used as a single breech-loader, and vice versa. Either can be called on at will, and the working of one will not interfere with the working of the other.

The arm is provided with a center lock of the usual pattern, and is cocked by the extension on the locking-bolt M when the trigger-guard is thrown down in the usual well-known manner. In rising, the carrier does not uncover the mouth of the magazine, and the cartridges cannot escape therefrom except when the carrier is forced down in line therewith for the reception of a cartridge.

I have provided a bolt, E, to prevent the escape of the gas from the bore as the arm is exploded, and it will also lock the carrier. It is movably attached to and works longitudinally in the carrier, and is operated as follows: As the locking-bolt M advances into and locks the carrier it will replace this bolt E, which will be moved forward, as in Fig. 1, into a recess, a, in the frame across the joint between the carrier-block and the wall of the frame, thereby cutting off the opening running down in front of the carrier-block, and thereby preventing any escape of gas from the bore into the magazine. As the locking-bolt is withdrawn a hook or nose, H, on the plate L of the locking-bolt drives this bolt E back into the slot in the carrier and leaves the carrier free to move down again as the lever is depressed.

I have shown an ordinary well-known single breech-loading attachment, which is adapted to work well on a magazine-gun of the pattern here shown.

The magazine being charged, the operation is as follows: The lever is thrown down. The finger on the arm of the guard will withdraw the locking-bolt and cock the gun, the finger meanwhile having traveled along in the groove of the carrier. At this point it exerts an in-

fluence on the carrier and moves it down until low enough to allow a cartridge to pass thereon from the magazine and replace the empty shell. The lever is now thrown back, which 5 will elevate the carrier, with its loaded cartridge, into line with the bore of the arm. The locking-block, when the carrier is up, will advance and lock the carrier firmly in place, leaving the hammer free to fall, and the arm 10 is ready for firing.

If it is desired to charge the arm from the breech and not from the magazine, the hammer is cocked and breech-plug is removed, with- 15 drawing the empty shell, when a new cartridge is passed into the chamber by hand and the breech-block closed, and the same is again ready for firing. It will thus be seen that the operator has the advantages of a single breech-loader or a magazine-gun.

20 The magazine is loaded in the usual well-known manner, while the operative parts are in their normal position, as in Fig. 1. This is done through an opening made in the side of the frame in line with the magazine, which 25 opening connects with the groove P in the carrier that opens into the mouth of the magazine. This opening in the side of the frame is covered by a longitudinal slide provided with a spiral spring, the tendency of which is to 30 force the slide to its closed position. To introduce a cartridge the point of the cartridge is placed against this slide and pressed forward until the cartridge passes the carrier-block and beneath the slide into the magazine. 35 The carrier-block will act as a stop to hold the cartridge in place in the magazine.

The manner of loading the magazine is shown in the Letters Patent to J. M. Marlin, December 9, 1879, No. 222,414.

40 O represents a hinged breech-block arranged to swing up and over to one side to open the breech of the gun, as in certain arms now or formerly manufactured. When the arm is used as a magazine-gun this block remains 45 closed, and at all times it constitutes the breech of the gun. When the gun is used as a single loader the magazine and the operating device or mechanism connected therewith remain inactive and undisturbed, and the loading is ef- 50 fected by opening the breech-block O.

It is apparent that the particular form or construction of the breech-closing mechanism, block, or device is not important, so long as the arm is adapted to be loaded and operated, 55 in either way at will, though that shown is preferred.

I am aware that magazine-bolt guns have been so constructed that the cartridge-carrier could be disconnected from the sliding bolt, 60 and that in a magazine-gun having the magazine in the stock and employing a swinging breech-block a stop has been provided to limit the movement of the block past the mouth of the magazine, both of which arrangements 65 permit the guns to be used as single-loaders.

My plan differs from these in that I provide a

breech-block which remains fixed when the magazine is in use, and which is in no way connected with the cartridge-carrier at any time; hence is always ready for operation without stopping to disconnect the carrier or otherwise adjust any part of the arm. 70

Having thus described my invention, what I claim is—

1. In a magazine fire-arm, the combination 75 of a vertically-moving carrier, a sliding locking-bolt, and a lever arranged, substantially as shown and described, to independently actuate the carrier and locking-bolt.

2. The reciprocating carrier provided with 80 slot J and locking-bolt, with plate containing slots, as shown, in combination with the guard G, having the arm T and transverse finger K, passing through and working in said slots, whereby the arm of the lever is worked in the 85 slots of a circle and produces an intermittent reciprocating movement in the carrier and locking-bolt, substantially as described.

3. In combination with a recessed carrier-block, a sliding locking-bolt adapted to enter 90 the recess of the block and connected with the operating-lever, substantially as shown and described, whereby the movement of the lever in one direction is caused to unlock the carrier-block, lower the same, and raise the hammer, 95 and the movement in the reverse direction is caused to raise the carrier-block and carry the locking-bolt into the recess thereof.

4. In combination with the carrier-block C, the extracting-band V, seated in the block and having a limited play therein, and a fixed stop or arm, U, arranged, substantially as shown, to limit the downward movement of the band V, as and for the purpose set forth. 100

5. The combination, with a barrel cut away 105 on its lower side, a vertically-moving block adapted to complete the barrel and to replace the portion cut away, and a plate adapted and arranged to extend across the line of union of the forward end of the block and the rear end 110 of the barrel, as shown and described, whereby the escape of gas at that point is prevented.

6. In combination with the recessed or grooved carrier-block C, mounted in a frame having recess a, the plate E, seated in the re- 115 cess of the block, as shown, and adapted to be moved outward at the forward end as the locking-plate enters the rear end, and thus to form a gas-check and to assist in locking the block.

7. The combination, in a gun, of a magazine, a charging or breech mechanism, substantially such as described and shown, adapted 120 to take cartridges from the magazine and deliver them to the firing-chamber, and a breech-closing mechanism permanently disconnected 125 from and wholly independent of the aforesaid charging mechanism, whereby the gun is adapted to be used at will either as a single-loader or as a magazine-gun without special adjustment of parts. 130

8. In a gun, the combination of a frame, a barrel, a magazine, a block, C, adapted to carry

- cartridges from the magazine to the barrel, and devices, substantially such as shown and described, for operating said block, and an independent breech-block, O, adapted to open and close the breech independently of the block C, and permanently disconnected from said block, whereby the gun may be at all times used either as a single-loader or as a magazine-arm without special adjustment of its mechanism.
10. 9. The combination of a barrel or frame, A, a breech-block, O, adapted to move across and to open and close the rear end of the barrel, a carrier, C, constituting a part of the barrel or cartridge-chamber, and having slot J, a sliding plate, E, mounted in the carrier and arranged to project therefrom across the line of unison of the carrier and barrel, a sliding lock-
- 15

ing-bolt, M, provided with a slotted wing, L, and a lever, G, provided with an arm, K, having a pin or stud to work in the slots of the block and locking-bolt.

10. In a fire-arm, the combination of a magazine, a breech-block adapted and arranged to take cartridges from the magazine to the point of firing and to constitute a portion of the barrel of the gun, and an independent breech-block in rear of and disconnected from the carrier, whereby the breech may be opened and closed without in any way affecting the magazine mechanism. 25
